& Young, LLP[57] **CLAIM**The ornamental design for a coin actuated vending machine
with linear game feature, as shown and described.**DESCRIPTION**

FIG. 1 is a perspective view of the claimed design;

FIG. 2 is a top view of the claimed design;

FIG. 3 is a side view of the claimed design;

FIG. 4 is a front view of the claimed design;

FIG. 5 is a back view of the claimed design; and,

FIG. 6 is a bottom view of the claimed design.
